UNITED STATES PATENT OFFICE.

DRAPER TREADWAY MARSHALL, OF VANCOUVER, BRITISH COLUMBIA, CANADA.

FOOD CABINET.

Application filed August 6, 1926. Serial No. 127,673.

My invention relates to improvements in food cabinets the objects of which are to provide means whereby the cabinet may be divided into separate compartments, one of which is insulated against the ingress of heat and is capable of use as a refrigerator using ice as a cooling medium, or to be equipped with an evaporator unit of a mechanical refrigerator system. Also to provide means whereby a circulation of air may pass from one compartment to another around the one insulated that they may be effectively ventilated during periods of high temperature when the insulated compartment is in use as a refrigerator, and to provide means whereby a circulation of air may pass through all the compartments during periods of low temperature, or when no extraneous cooling medium is used in the insulated compartment.

The invention consists essentially of a ventilated cabinet having an insulated compartment disposed intermediate its height and spaced apart from some of the side walls of the cabinet, said insulated compartment being provided with closable openings in its opposite side walls, so that the air flowing through the cabinet may also flow through the insulated compartment, as will be more fully described in the following specification, in which:—

Fig. 1 is a sectional view of the invention taken on the line 1—1 of Figure 3.

Fig. 2 is a front view.

Fig. 3 is a sectional view taken on the line 3—3 of Figure 1.

Fig. 4 is a sectional view taken on the line 4—4 of Figure 1.

In the drawings like characters of reference indicate corresponding parts in each figure.

The numeral 1 indicates generally the cabinet having a bottom wall 2, a top wall 3, side walls 4, a rear wall 5 and a front wall 6. The cabinet may be formed as an integral portion of the building, wherein one or both side walls or the rear wall may be portions of the walls of the building. The rear wall 5 is provided with a pair of ventilating grilles 7, one adjacent the bottom wall 2 and the other adjacent the top wall 3, so that air may enter through one and after circulating through the cabinet pass outwards through the other, thus providing a suitable ventilation during the cool weather for keeping foodstuffs housed therein, in good condition.

The front wall 6 is provided with a pair

of doors 8 adjacent the top and bottom thereof, which are suitably fitted with hinges 9 and catches 10, and intermediate the vertical length of the wall is a suitably insulated door 11 preferably fitted with refrigerator hinges 12 and fastener 13. Fitted to the rear of the front wall 6 is a refrigerator compartment 14 which is slightly less in cross sectional area than the cabinet 1 to provide a plurality of spaces or air ducts 15. This compartment divides the cabinet to define a lower compartment 16 and an upper compartment 17 both of which may be fitted with shelves 18 if desired. The refrigerator compartment 14 is provided with insulated side and rear walls 19 and top and bottom walls 20 having apertures 21. These apertures are adapted to be closed by removable plugs 22 which are made of sheet cork or other non-conducting material and are preferably held in place by friction, though any other holding means may be adopted.

The numeral 23 indicates a suitably supported tray having a drip pipe 24 extending therefrom, which is conducted to discharge outside the cabinet 1 as desired, this tray is adapted to be filled with ice, or to form a support for an evaporating unit of a mechanical refrigerating system. The insulated compartment is provided with one or more adjustable shelves 25.

Having thus described the several parts of my invention I will now briefly explain its function.

The cabinet is assumed to be fitted with its ventilating grilles 7 in communication with air ducts extending through an outside wall of the building. During the warm weather when refrigeration is desirable and the quantity of perishable foodstuffs carried in the home is relatively small, the plugs 22 are set into the apertures 21 of the insulated compartment 14, a cooling medium used and the foodstuffs stored therein. Foodstuffs of a semi-perishable nature, such as bread or other things which will keep at normal temperatures, being stored in the lower or upper compartments 16 and 17 where they are subjected to ventilation consisting of a flow of air entering through one of the ventilating grilles 7 and its compartment, thence through the ducts 15 between the insulated compartment and the walls of the cabinet, through the other compartment and finally outwards through its ventilating grille. In the cooler weather, the use of ice or other cooling medi-

um in the insulated compartment may be dispensed with and the entire cabinet used as a unit under an equal temperature throughout its several compartments by removing the 5 plugs 22 and allowing a flow of air to pass therethrough.

It will thus be seen that I have invented a food cabinet having upper and lower food compartments and an insulated intermediate 10 compartment capable of being used as a refrigerator when required, and when so used an adequate fresh air ventilation is provided to the other compartments, also, that during such times as refrigeration is not required 15 that fresh air ventilation is continuously provided through all the compartments.

What I claim as my invention is:

A food cabinet comprising a casing having top and bottom openings for the circulation 20 of air therethrough and provided with upper, lower and intermediate doors giving access to corresponding interior portions of the casing, the upper and lower portions of the casing being provided with shelves designed 25 to support food or other articles therein without obstructing the passage of air through the casing, an insulated compartment

occupying the intermediate portion of the casing and secured to that wall portion of the casing by which the said intermediate door is carried and being accessible through said door, said insulated compartment being spaced from the remaining surrounding wall portions of the casing to provide air flow passages connecting the upper and lower portions of the casing between which the insulated compartment is situated, refrigerant and article supporting means contained within said insulated compartment, there being openings formed in the top and bottom wall 40 portions of the insulated compartment to permit air to pass through as well as around said compartment when outside temperature conditions are such that circulation of outside air through the casing and compartment is sufficient to preserve the articles contained 45 therein and means for closing the openings in said compartment when temperature conditions are such as to require the use of a refrigerant therein. 50

Dated at Vancouver, B. C., this 19th July, 1926.
